UNITED STATES PATENT OFFICE.

ORVILLE H. ENSIGN, OF PASADENA, CALIFORNIA, ASSIGNOR TO ENSIGN CARBURETOR CO., OF LOS ANGELES, CALIFORNIA.

CARBURETER.

1,316,149.

Specification of Letters Patent.

Patented Sept. 16, 1919.

Application filed September 28, 1915. Serial No. 52,307.

To all whom it may concern:

Be it known that I, ORVILLE H. ENSIGN, a citizen of the United States, residing at Pasadena, in the county of Los Angeles and 5 State of California, have invented new and useful Improvements in Carbureters, of which the following is a specification.

This invention relates to certain means combined in carbureters of the vortex mixing-chamber type invented by me and illustrated in some of its forms in my Letters-Patent of the United States Numbers 1,064,627 and 1,064,628, dated June 10, 1913, and in my application for Letters-Patent of 15 the United States Serial No. 732,746, filed Nov. 21, 1912, and also in Letters-Patent of the United States Number 1,108,727 granted to me Aug. 25, 1915, upon assignment of my son, Roy Francis Ensign.

20 This invention is applicable to other types of carbureter.

In practical operation with this recently patented type of carbureter, air, by suction of the motor, is drawn through a tangential 25 air inlet or horn into a circular vortex chamber having an axial outlet, through which the air passes after taking on a circular motion due to its inertia and the circular walls of said chamber. The air body within the 30 vortex chamber whirls about the central axis of said chamber before finding exit at said outlet; and because of such whirling motion, the body has a gradient of pressure diminishing from the periphery inward, becoming 35 denser toward the circular confining walls and rarer toward the center of the chamber; and the difference between the high peripheral and low axial pressures thus induced vary; increasing when the speed or load of 40 the motor increases and decreasing when such speed or load decreases. The liquid fuel is fed to the center of the vortex and is drawn in by this lowered pressure.

45 It is a well-known fact that internal combustion motors are required to run at various speeds and also that greatest economy and efficiency can only be secured by supplying the engine with correct mixture of liquid fuel and air.

50 It is also a well-known fact that an engine will require a richer mixture, that is to say a greater proportion of liquid fuel to the amount of air used when running under throttled low speed, than when running at 55 full power at high speed. The reason for

this is that at throttled low speed running, the full charge of air is not drawn in and hence the compression is low in the cylinders; while at full power with wide-open throttle, full charges are drawn in and hence 60 full compression of the mixture is obtained; and a more intimate association is effected between the molecules of the fuel and molecules of oxygen. It is therefore necessary 65 at extreme low speeds to have a richer mixture, so-called, in order to keep the engine working smoothly. It has been found that under the lighter pressure, intimate association of the molecules can only be attained by excess of fuel.

In this particular type of carbureter a vortex is used as a means of creating a mixture, and the mixture produced by this type of carbureter when adjusted to a definite proportion at any speed remains very nearly 70 constant at all speeds; but there is a slight tendency to a richer mixture at lower than at higher speeds and this is exaggerated in said carbureter when applied to some motors.

The reason that the mixture is slightly 75 richer at the lower than at the higher speeds is as follows: The body of air within the vortex mixing chamber revolves freely under the impelling force of the velocity of 80 the air entering the air horn. The velocity of this entering air is directly proportional to the volume of air passing through the carbureter. Were there no friction on the inner walls of the mixing chamber the suc- 85 tion at the center of the mixing chamber would be such as to produce an absolutely constant proportion of liquid fuel and air at all speeds; but the centrifugal action causes the air body to press upon the inter- 90 nal surface of the walls of the mixing chamber more strongly at the higher speeds. This causes a braking effect on the whirling 95 air body that increases as the speed increases, thus reducing the revolutions of the air body 100 in the chamber, proportional to the mass of air passing through the carbureter. This braking effect lowers the vortex suction on the liquid fuel feed orifice and hence pro- 105 duces a slightly weaker mixture at the higher speeds and power than is produced at the lower speeds and power. Thus it is seen that although the natural mixture produced by this vortex carbureter conforms closely to the natural demands of the internal combus-

tion motor, a difficulty arises in fulfilling conditions imposed by the extreme low-speed idling of the motor that is so desirable in automobile practice, and an object of this invention is to avoid this difficulty.

It is also desirable to be able to adjust both idling and power mixtures to suit the different types of motors.

An increase of throttle opening with an internal combustion motor results in a corresponding increase of compression so that such motor can, at each increase, take and utilize to the best advantage a weaker mixture than the previous one. The maximum compression can make the best use of the weakest possible mixture consistent with perfect combustion.

It is therefore desirable that means be provided whereby the mixture with throttle closed will be of maximum richness in fuel and as the throttle opens the mixture will diminish in such richness and will be weakest when the throttle is wide open.

There are great variations in motor designs, and different motors have different proportions of bore and stroke, valve area, valve lift and valve timing. Consequently as the air flows through the carburetor in a series of waves or impulses of velocity produced by the suction of individual cylinders, the shape of the waves of impulses differ greatly with different designs of motors. This exaggerates the need in some motors, for a richer mixture at low speeds and a weaker mixture at high speed, notwithstanding the fact that there are many designs of motors that will take the natural mixture produced by said carburetor.

To be able to meet the conditions imposed by the demands in many motors for the extremely rich mixture at low speeds I have invented two devices operating together in some instances, and separately in others; one consisting of a specially constructed butterfly damper pivotally hung in a circular air intake and hereinafter described.

The automatic regulation of the mixture to suit the various speeds and loads is thus made practically perfect for a given motor but it is necessary, in order to produce the best results, that some means be provided to further regulate the working mixture to suit different motors. I have accomplished this by controlling the orifice supplying fuel to the mixing chamber, and this is done by means of a sleeve which may be screwed over the fuel orifice that is always drilled too large for the best mixture and thus to adjust the opening to supply the requisite amount of fuel to give the best idling mixture in combination with the action of the butterfly valve above described. Having now obtained the best idling mixture for the given motor, there may still be required another adjustment for maximum power

and speed, and for this purpose a small air valve is provided which is weighted to open at an average speed found necessary in practice by the suction of the vortex on different types of motors as hereinafter more fully set forth.

The invention can be carried out in various ways and comprises a carburetor provided with certain effective means to maximize the richness in fuel when the throttle is closed and also comprises a carburetor provided with certain effective automatic means to diminish the richness in fuel as the throttle is opened. Other features and combinations of the invention will more fully appear in the subjoined detail description.

The accompanying drawing illustrates the invention as applied in approved form in a vortex type of carburetor and any internal combustion motor.

Figure 1 is an axial elevation of fuel-adjusting means constructed in accordance with this invention. Parts are broken away to expose features of construction otherwise hidden. Lines x^1-x^1 , Figs. 3 and 4 indicate the plane of section. The parts are shown in solid lines in slow idling position. Dotted lines indicate the position at which the butterfly will hang when only subject to the force of its own gravity. The heavy dotted arrows indicate the direction of the pressures during operation, and the suction-controlled valve is shown raised in dotted lines. Only a fragment of the engine is shown as the construction and operation of the same in many types and forms are well known to those skilled in the art.

Fig. 2 is a plan section on line x^2 , Fig. 1.

Fig. 3 is a plan section in reduced scale on irregular line x^3 , Fig. 1. Line x^3 , Fig. 4 also indicates the plane of section.

Fig. 4 is a sectional elevation on line x^4 , Fig. 3, the reduced throat being indicated in part by dotted lines.

Fig. 5 is a detail of the suction regulating valve as under high speed, full power stroke.

Fig. 6 is an axial section of the suction tube at right angles to Fig. 1.

Fig. 7 is an enlarged fragmental sectional detail illustrating the means for regulating the size of the fuel orifice.

1 is the vortex chamber having a central mixture outlet 2 at one end and a central liquid fuel inlet 3 at the other end. The suction pipe or bottom L^4 applies the engine suction at the mixture outlet 2 to suck air through said vortex chamber. Said bottom L^4 being connected to and made effective by the engine, a fragment of the manifold 5 of which is shown, is controlled by a throttle 6; said engine and throttle being of any well known construction. The vortex chamber is provided with an air inlet horn 7 having a cylindrical intake bore 8 and a reduced throat 9 leading from the in-

take mouth or bore 8 and opening tangentially into the vortex chamber 1 at one side thereof, so that air sucked therethrough by suction in the bottom L^4 will produce a vortex with low central depression producing suction on the fuel inlet 3.

A pivotal support 10 extends through said bore, its axis intersecting and being at right angles to the axis of said bore and serving 10 as a pivotal support for a thin butterfly valve that is mounted to revolve freely on said support 10 in said bore 8; the lower vane 11 of said butterfly valve practically conforming in contour to the lower arc of said bore 15 8 and to the throat 9 when swung adjacent thereto; and the upper vane 12 of said butterfly valve being practically equal in area to about three-fourths, more or less of the area of the lower vane 11 so that under a 20 low suction at said mixture outlet, an increase or a decrease of the vertical depression will cause an adjustment of the angle of the butterfly with the bore and throat and a corresponding increase or decrease in 25 the size of the inlet opening 13 above the axis of the support.

A suction chamber 14 is provided communicating through the central inlet 3 with the center of the vortex chamber and a suction 30 reducing air lift valve 15 operable by the depression at the inlet 3 is provided to admit air to the suction chamber 14 to lower the suction in chamber 14, thus to limit the liquid fuel flow to an amount determined by 35 experiment for a particular motor.

The sequence of events in the operation of the butterfly and the air lift valve 15 varies with different motors. At the slow idling speed of an automobile motor the butterfly 40 11, 12 will take about the angle shown in solid lines in Fig. 1 of the drawings. As the motor is speeded up at some speed not very much greater than the idling speed the butterfly will take the horizontal position 45 shown in dot-and-dash lines in said Fig. 1, usually between seven and ten miles an hour on the direct drive gear in most cars. In present practice with this invention, the butterfly valve is preferably made to reach 50 the horizontal position when a suction pressure of four inches of water at the center of the vortex mixing chamber is reached, and to stand there until the pressure falls below that point. This adjustment is determined 55 at the factory.

The valve 15 in some cases may lift before the butterfly has taken the horizontal position and in some cases after it has taken such position; and in many cases when 60 motors are new and there is no leakage about the valve stems it may be adjusted so that it does not lift at all. This is especially so with multi-cylinder motors, that is, six cylinders, eight cylinders or more, which are of 65 such a character as to produce a steady

flow. The weight of the valve is the same for all carburetors of the same size independent of the type of motor to which it is applied, but the length of lift is made adjustable to suit different motors. This is done 70 by means hereinafter described.

The inward taper of the upper surface of throat 9, begins at such point as that the opening underneath the lower limb 11 does not increase so rapidly as the opening above 75 the upper limb 12, and therefore the pressure of the inflowing air is more effective to open the valve than would be the case if the throat were not contracted.

Constant level fuel-supplying means are 80 provided for supplying liquid fuel to the suction chamber 14 through the fuel orifice 14' in the walls thereof. Said means comprise a constant level chamber 16 and float 17 in said chamber connected to a lever 18 85 pivotally mounted on a pivot 19 extending through the fuel passage 20 in which a fuel port formed by a valve seat 21 admits liquid from a fuel liquid strainer chamber 22 connected by pipe 22' to a reservoir or tank 90 not shown; said float and the lever 18 acting upon the loose washer 23 to close the valve 21 when the float rises and acting through the loose washer 24, the spring 25 and collar 26 on valve stem 27 to open the valve when the 95 float 17 falls, said fuel orifice 14' constituting restricted means to admit liquid fuel to the suction chamber 14. A suction tube 28 communicating between the suction chamber 14 slightly above the liquid level 29 therein 100 and with the central liquid fuel inlet 3 of the vortex chamber, constitutes means for applying suction from the center of the vortex in the vortex chamber to the suction chamber, and affords means to variably discharge liquid fuel from the suction chamber under the various degrees of vacuum produced by vortical depressions. Regulable means are provided to adjust the restricted 105 liquid fuel admitting means or orifice 14'. 110 Such regulable means as shown consists in a collar 30 threaded upon the wall of the suction chamber 14 and adjustable across the restricted fuel orifice 14' by screwing the collar up and down on the chamber. The suc- 115 tion tube 28 is adjustable as to height by means of a screw-driver in kerf a to suit the pressure on the fuel formed in different installations. The tickler 32 may be operated by a connection 33 and spring 34 to force 120 the float 17 down and to release it in the usual manner for causing an extra flow of liquid fuel for the purpose of enriching the mixture at starting.

The suction reducing means are connected 125 with the suction chamber 14 opposite to the suction tube 28 and comprise a valve head 35 screwed on the top of the suction chamber 14 and provided with inlet ports 36 leading to a passage 37 closed by the valve 15 130

that has a stem 39 working in an axial valve stemway 40 in an adjusting screw 41 that is screwed down into a cap 42 screwed onto the valve head.

5 Said valve head has a valve chamber 43 from which passages 44 open into the suction chamber 14. The valve 15 seats by gravity upon the valve seat 38 formed at the top of the valve passage 37, and whenever 10 the suction at the vortical center reaches a predetermined value or degree, the atmospheric pressure on the under face of the valve 15 lifts said valve and allows atmospheric air to flow into the suction chamber 14 so 15 that from that time on the discharge of liquid fuel through the suction tube 28 is proportionately lessened at the high speeds of the motor.

In constructing the apparatus the suction 20 pipe may have a connection 45, which carries the throttle 6; said pipe connecting the manifold of said engine and the vortex chamber 1.

Said vortex chamber with its air horn are 25 cast in a single piece to fit on the elevated rim 46 of said bottom L⁴; the interior of which tapers downwardly at its intake from the downwardly tapering vortex chamber. Said vortex chamber terminates in a trough 47 30 surrounding an annular upwardly projecting edge 48 that forms the margin of the mixture outlet 2. A drain port 49 leading from said trough 47, discharges into the suction pipe 4 between said orifice 2 and the 35 outlet from said pipe 4, the drainage of liquid fuel accumulated from the vortex chamber walls. Said drainage falls into the current of air flowing from said orifice 2 to the engine.

40 The usual bolt 50 shown in some of said former patents extends up through the suction pipe 4, and the outlet 2 into the chamber 1; and the conical deflector 51 is provided with a fuel connection 52 forming the central inlet 3 and is mounted on said bolt 50; said connection 52 having an upwardly extending externally and internally threaded bushing 53 into the top of which the suction tube 28 is adjustably screwed. Upon this 45 bushing 53 is screwed the constant level fuel chamber 16 which is provided with an annular groove 54 to fit upon the upper rim of the vortex chamber 1; and the suction chamber 14 is screwed down upon the bushing and against chamber 16 to hold chamber 16 firmly in place.

The cover 55 for the constant level liquid fuel chamber 16 is provided with a hollow depression 56 having a central opening 57 60 that fits the smooth cylindrical exterior of the suction chamber 14; the inner walls of the depression 56 fitting over the lower portion of the valve head 35 which is internally threaded and is screwed upon the threaded 65 top of the suction chamber 14, thus firmly

fixing the cover 55 in place. The bolt 50 is preferably threaded at both ends and provided with nuts 57, 58 adjustable thereon to exactly position the parts assembled.

In practical operation at low speeds the 70 butterfly valve serves to choke the air inlet so as to add to the vertical suction at the inlet 3 during the extremely low vertical pressures due to the low speed, so that the mixture at the low speeds is proportionately 75 richer as required for the reasons set forth in the brief statement of the invention at the beginning of this specification. This choking and consequent enriching of the mixture continues until the butterfly valve is 80 swung to the horizontal position.

When the adjusting screw 41 is set it is held by the spring 58 from being unscrewed by vibrational action.

The resistance produced by the butterfly 85 under idling conditions amounts to about one-fourth of an inch of water pressure, while the natural suction pressure placed upon the fuel by the natural action of the vortex mixing chamber gives about three-fourths of an inch. It will be noticed that this adds suction pressure to the liquid fuel of about thirty per cent., which is found in practice sufficient for all needs. Upon attaining a higher speed the butterfly comes 90 wide open and remains in a horizontal position, floating on the air similar to the wings of an aeroplane. As the butterfly is moved from the idling to the horizontal position the resistance it offers becomes less and less; 95 actual measurements showing it to be not more than one-eighth of an inch of water pressure when the suction pressure at the center of the vortex is twenty inches of water pressure.

100 In other words, at the idling speeds the butterfly serves as automatic means to add materially to the normal vortex suction and at any other speeds than the idling speeds the added suction produced by the butterfly is negligible.

A delicately unbalanced butterfly valve swinging freely in the circular air inlet to the vortex chamber is necessary for perfect working in order to adjustably choke the 115 air inlet to afford requisite fine variations of vortex suction at the fuel inlet 3 from the closed throttle position shown in solid lines in Fig. 1 when only a very small amount of air is drawn through the vortex chamber at each impulse of the engine, on up to the position of throttle where the butterfly is fully opened to horizontal position.

120 Attention is directed to the arrangement 125 of the suction regulating valve relative to the mixing chamber; the same being so arranged that as the suction is increased at the center of the vortex the fuel supply is diminished, and at the same time the fuel 130

laden air is more violently drawn through the annular outlet into the bottom L⁴, where the direction of travel of the whirling mixture is changed and as the violence of the 5 vortical or whirling action increases and the quantity of the fuel supplied to the air decreases, the most intimate admixture of fuel with the air is effected; so that upon compression in the combustion chamber of the 10 engine, the mixture is in superior condition for complete combustion.

I claim:

1. A carbureter provided with a downwardly diminishing mixing chamber having 15 a lateral air inlet and an annular mixture outlet opening downwardly therefrom, a suction chamber through which the fuel passes to the upper portion of the mixing chamber, and automatic means to admit air 20 to the suction chamber when the suction at the mixing chamber is great, to reduce the suction in said suction chamber and thereby reduce the flow of liquid fuel.

2. A carbureter of the vortex type provided with a downwardly discharging mixing chamber and a suction chamber thereabove through which the fuel passes to the vortex mixing chamber, and automatic means to admit air to the suction chamber 30 to reduce the suction in said suction chamber and thereby reduce the flow of liquid fuel when the vortical action is violent.

3. In a carbureter of the vortex type a suction chamber through which liquid fuel 35 is supplied to the vortex mixing chamber; means to maximize the richness in fuel when the vortical action is low and automatic means to admit air to the suction chamber to diminish the richness in fuel as the vortical 40 action is increased.

4. In a carbureter, fuel-adjusting means comprising a chamber maintaining fuel at a constant level, a vortex chamber, a suction chamber within the constant level chamber, 45 means for applying suction from the center of the vortex to the suction chamber, means consisting of a valve seated by gravity adapted to be lifted by the suction of the chamber for weakening the suction in the 50 suction chamber, and an adjusting screw for controlling the amount of lift of said valve; the air admitted through said valve reducing the suction in the chamber, and hence, reducing the proportionate amount of fuel 55 admitted to the chamber.

5. In a carbureter, fuel-adjusting means comprising a chamber maintaining fuel at a constant level, a vortex chamber, a suction chamber within the constant level chamber, 60 means for applying suction from the center of the vortex to the suction chamber, means for supplying fuel through a restricted orifice to the suction chamber, means consisting of a sleeve over the outside of the suction chamber arranged to adjustably cut off 65

portions of the orifice, an air valve seated by gravity lifted by the suction in the suction chamber when the suction reaches a determined degree, and an adjusting screw to control the lift of said valve.

6. In a carbureter, fuel-adjusting means comprising a chamber maintaining fuel at a constant level, a vortex chamber, a suction chamber within the constant level chamber, means for applying suction from the center of the vortex to the suction chamber; means for admitting fuel through a restricted orifice to the suction chamber, an unbalanced butterfly valve supported on a shaft extending through the axis of the circular air inlet to the vortex mixing chamber, a sleeve for cutting off a portion of the orifice for adjusting the area of the fuel orifice, an air valve lifted by suction when the suction in the suction chamber reaches a predetermined degree, and an adjusting screw to control the amount of lift of said valve.

7. In a carbureter, fuel-adjusting means comprising a chamber maintaining fuel at a constant level; a vortex mixing chamber; means consisting of a tube adapted to be raised and lowered to maintain its upper end just above the fuel level in the constant level chamber; means for applying suction from the center of the vortex chamber; means for admitting fuel through a restricted orifice to the suction chamber; means for admitting air to the suction chamber after the suction has reached a determined degree; means for adjusting the amount of air thus admitted; and means for passing liquid fuel from the suction chamber to the vortex chamber.

8. In a carbureter, fuel-adjusting means comprising a chamber maintaining fuel at a constant level; a suction chamber within the fuel chamber; a vortex mixing chamber; means for applying suction from the center of the vortex to the suction chamber, within the constant level chamber; means for admitting fuel through a restricted orifice to the suction chamber; automatic means for admitting air to the suction chamber after the suction has reached a determined degree; means for adjusting said automatic means to determine the amount of air thus admitted; and means for passing liquid fuel from the suction chamber to the vortex chamber.

9. In combination, a mixing chamber having a central outlet at one end; means to cause suction at such outlet; an air inlet opening tangentially into said chamber at one side thereof; a support the axis of which extends at right angles through the axis of the air way; a thin butterfly valve mounted to oscillate on said support; the lower vane of said butterfly valve practically conforming to the inside of the air inlet and swing-

6
ing freely in said inlet; the upper vane of said butterfly valve being about $\frac{2}{3}$ ths the area of the lower vane, there being thus formed above said butterfly valve, a contracted opening so that air is normally admitted under a low suction and variations of pressure above extreme low suction, will cause corresponding increase and decrease in the size of the inlet until the valve is supported in a horizontal position by the current; a suction chamber communicating with the center of the vortex chamber opposite the central outlet; and a valve operable by high suction to admit air to relieve the suction in the mixing chamber.

10. In combination a vortex chamber having a central mixture outlet at one end and a central liquid fuel inlet at the other end; means to cause suction at such outlet and thereby to induce suction at the fuel inlet; an air inlet horn having a cylindrical intake bore and a reduced throat leading from the intake bore and opening tangentially into said chamber at one side thereof; a pivotal support extending through said bore and intersecting the axis of said bore at right angles; a thin butterfly valve mounted to revolve freely on said support in said bore, the lower vane of said butterfly valve practically conforming in contour to the lower arc of said bore and throat; the upper vane of said butterfly valve being practically equal in area to about three-fourths the area of the lower vane so that under a low suction at said mixture outlet, increase and decrease of the suction pressure will cause an adjustment of the angle of the butterfly with the bore and a corresponding increase and decrease in the size of the inlet orifice above the axis of the support by giving a greater or less inclination to the butterfly valve, thereby enlarging or diminishing the inlet orifice; a suction chamber communicating with the central inlet to the vortex chamber; a suction-reducing valve operable by suction applied at the center of the vortex to admit air to the suction chamber to relieve suction in the suction chamber at a time after the butterfly is fully opened by suction at the center of the vortex; constant level means to

maintain a supply of liquid fuel for the suction chamber; restricted means to admit liquid fuel from the constant supply means to the suction chamber; means to variably discharge liquid fuel from the suction chamber under various suction pressures and regulable means to adjust the restricted liquid fuel admitting means.

11. In a carbureter, means for enriching fuel mixture of internal combustion motors at extreme low idling speeds, comprising in combination, a carbureter mixing chamber, an inlet horn forming a circular air inlet and having a horizontal axis, an outlet for said mixing chamber, means whereby air is drawn through said inlet and mixing chamber by the action of the motor; a slightly unbalanced thin butterfly valve mounted to oscillate on a horizontal axis that intersects the axis of said air inlet; the rim of the lower half of the butterfly valve practically closing the lower half of the horizontal air inlet when the valve is vertical; the upper half of said valve being of reduced area as compared with the area of the lower half of the valve so that the passage below the axis is closed and there is an open air passage above said horizontal axis of the valve between its upper edge and the walls of the air inlet when the valve is vertical. 80

12. In a carbureter, fuel-adjusting means comprising a constant level fuel chamber, a suction chamber communicating with the constant level fuel chamber, a vortex chamber, means for applying suction from the vortex chamber to the suction chamber, valve means adapted to be lifted by the suction of the suction chamber and thus reducing the suction in said chamber and hence the proportionate amount of fuel admitted to the chamber, and adjusting means for controlling the amount of the lift of said valve.

In testimony whereof, I have hereunto set my hand at Los Angeles, California, this 18th day of September, 1915.

ORVILLE H. ENSIGN.

Witness:

JAMES R. TOWNSEND.

It is hereby certified that in Letters Patent No. 1,316,149, granted September 16, 1919, upon the application of Orville H. Ensign, of Pasadena, California, for an improvement in "Carbureters," an error appears in the printed specification requiring correction as follows: Page 4, line 72 and line 73, for the word "vertical" read *vortical*; and that the said Letters Patent should be read with this correction therein that the same may conform to the record of the case in the Patent Office.

Signed and sealed this 14th day of October, A. D., 1919.

[SEAL.]

M. H. COULSTON,

Acting Commissioner of Patents.
